UNITED STATES PATENT OFFICE.

FREDERICK JACKSON PRATT, OF DETROIT, MICHIGAN.

GAUGE FOR DETERMINING INTERNAL DIAMETER OF ELEMENTS BEING GROUNDED.

Application filed January 17, 1924. Serial No. 686,938.

To all whom it may concern:

Be it known that I, FREDERICK JACKSON PRATT, citizen of the United States, residing at Detroit, county of Wayne, State of Michigan, have invented a certain new and useful Improvement in Gauges for Determining Internal Diameter of Elements Being Ground, and declare the following to be a full, clear, and exact description of the same, such as will enable others skilled in the art to which it pertains to make and use the same, reference being had to the accompanying drawings, which form a part of this specification.

15 My invention relates to a gauge for automatically measuring the bore or internal diameter of an element being ground.

One object of the present invention is to provide a device which will insure accuracy 20 of measurement throughout the entire length of the element calipered while the latter is being ground to size.

A further object of the invention is to increase production due to the speed with 25 which articles may be ground without stopping the grinding machine to take measurements.

A further object is to provide a device so constructed and mounted that it may maintain its proper relation to the article being 30 ground throughout the entire period of grinding.

A further object of the invention is to provide a device which may be swung out 35 of the way to remove or replace the article to be ground.

A further object of the invention is to provide against any appreciable wear;—even after long periods of service in traversing the bore or element calipered,—by employing diamonds, sapphires, or other gem stones for the stylus points.

One object in constructing the stylus 45 points of diamonds is that they may break through the fluid film covering the surface of the element being ground that an exact measurement may be obtained without cutting or scratching the surface measured.

A further object of the invention is to 50 provide a device which is readily adjustable to meet the requirements of different articles to be calipered.

With the foregoing and other objects in 55 view which will appear as the description proceeds the invention further resides in the combination and arrangement of parts and

in the details of construction hereinafter described and claimed it being understood that changes may be made in the precise embodiment of the invention herein disclosed without departing from the spirit of the same.

In the drawings accompanying this specification:

Figure 1 is an end elevation of the device 65 attached to a grinding machine showing the article to be ground in contact with the grinding wheel,—indicated in dash and dotted lines.

Figure 2 is a plan view of the device, 70 with the dial indicator removed, secured to a fragmentary portion of the frame of a grinding machine as it would appear when measuring the bore or internal diameter of an element being ground,—a fragment of 75 which is shown in cross-section.

Figure 3 is a plan and sectional view of the device taken on or about line 3—3 of Figure 1, indicating the stylus arms of the gauge swung out of operative position;— 80 showing a fragment of the grinding machine and sectional view through the article being ground,—as in Figure 2.

Referring now to the letters of reference placed upon the drawings:—

A, designates a grinding machine, B, denotes a grinding wheel, C an article being ground and calipered.

D, represents a pulley and E indicates the driving belt.

F, denotes a bracket bolted to the frame of the machine and G designates a socket member pivoted at F^a to the bracket adapted to receive a standard or rod G^a, secured in the socket member by a set screw g.

G¹, denotes an arm integral with the socket member, slotted at its lower end to receive a bolt G², screwed into the bracket F. G³ indicates a spring sleeved upon the bolt adapted to bear upon the arm G¹ to 100 normally restore the rod G to a vertical or predetermined position. G⁴ represents an adjustable set screw extending through the arm G¹ adapted to bear upon the bracket to limit the movement of the rod under the 105 urge of the spring G³.

H, designates a divided clamping member adjustably secured to the upright rod G^a, by a bolt H^a.

Extending transversely through the 110 clamping member H, and secured thereto by a bolt H^b, is a bracket arm I, provided at

one end with a yoke I^a in which is supported by a pair of adjustable pivot screws J, J , a bracket K having a forwardly extending arm K^a —and projecting from its upper face adjacent its end is a lug K^b , adapted to receive a swinging yoke arm L , pivoted to the bracket K , by a pair of pivotal bolts L^a, L^b ,—the outer end of the yoke arm L , being formed with a divided socket L^b , adapted to support a rod M , adjustably secured in the socket by the bolt L^c .

N , denotes a bar clamped in the divided forward end of the swinging member L , by a bolt P .

15 Q , designates an adjustable slotted arm secured to the end of the bar N , by a set screw Q^1 , extending through a beveled block Q^2 , bearing upon the inclined or beveled walls of the slotted arm.

20 R , represents a diamond or gem stone mounted in the end of the arm Q ,—which is adapted to contact with the periphery of the element to be ground.

The lower end of the bar M , is fitted 25 with a divided clamping block S , adapted to receive a bar T , adjustable therein;—on the forward end of which is mounted a slotted arm T^a , adjustably secured to the bar by a set screw T^b .

30 R^a , denotes a diamond or gem stone set in the end of the slotted bar T to impinge upon the periphery of the work being ground.

35 U , represents a bracket member clamped to the upper end of the bar M by a bolt U^1 having an arm U^2 to which is clamped an indicating dial W , of usual construction, the depending finger W^1 of the indicating dial controlling the movement of the swinging pointer W^2 which bears upon an arm X , having a yoke-shaped end X^a pivoted to the bracket U , by a pair of pivotal screws V, V .

Integral with the arm X , is an extension 45 X^b , adapted to support an adjustable slotted arm Y , to which it is secured by a set screw Y^a .

R^b , denotes a gem stone fitted to the end of the slotted arm Y , to impinge upon the periphery of the work to be calipered.

For the sake of convenience the device 55 may be said to consist of a support, an adjustable frame on the support comprising the bracket arm L , yoke member I^a , bar U and vertical standard M on which the arms carrying the gems are adjustably mounted, the member N being capable of oscillation in the yoke member to swing the adjustable arms toward and away from the work.

Having now indicated the several parts by reference letters the construction and operation of the device will be readily understood.

A template or master element (not shown)

of predetermined internal diameter is first mounted in the grinding machine. The grinding gauge is then adjusted to the position indicated in Figure 1, in which the oppositely disposed diamond points R^a and 70 R^b , supported respectively by the arms T^a and Y , may impinge upon the inner surface of the template on a plane intersecting its longitudinal axis,—the arm Q being adjusted so that the gem stone R , will impinge upon the internal periphery of the template, midway between the gem stones R^a and R^b . In adjusting the gem stones to impinge upon the periphery of the template, care should be exercised to insure the 75 rotatable pointer W^2 of the dial indicator W , registering at zero,—it being evident that when the element to be ground is inserted in the grinding machine in place of the template the pointer will move from its zero position to a point indicating the relatively smaller diameter of the element to be ground.

The gauge having been properly adjusted the device is swung horizontally upon its pivotal support J, J , to the position indicated in Figure 3,—the template is then removed from the grinding machine that it may be replaced by the element to be ground. The gauge is then returned to its former position, as indicated in Figures 1 and 2. Power is then applied to actuate the grinding machine,—the operator taking careful note of the dial indicator reading as it gradually registers the difference in the internal bore of the element being ground.

It will be understood, of course, that as the element to be ground is rotated in the usual direction it reciprocates in front of the grinding wheel that the internal bore of the element may be uniform throughout its length.

Upon the pointer of the dial indicator registering "zero" the grinding process is stopped that the operator may remove the element which is then the exact diameter of the template. The gauge supporting frame is then again swung to the position indicated in Figure 3 that the element ground may be removed to be replaced by another element to be ground,—whereupon the operation just described is repeated.

To maintain the gem stone R carried by the arm Q in impinging relation with the periphery of the element being ground the spring G^a mounted upon the bolt G^2 , screwed in the bracket F , is adapted to bear upon the depending arm G^1 , integral with the socket G in which the upright rod G^a is mounted. The action of the spring causes the rod G^a to tilt causing the arm Q to move laterally that its gem stone R may impinge upon the periphery of the element being ground as the diameter of the bore is gradually enlarged through grinding. The ad-

justable screw G^4 supported in the arm G^1 changes made in the diameter of the bore of the annular element while being ground.

Having thus described my invention what

5 I claim is:

1. In a device of the character described, a frame comprising a plurality of adjustable elements connected together to form a unitary structure including a plurality of independently adjustable arms secured to the frame at one end, means connecting the arms to the frame for oscillation into and out of an element to be internally ground, a gem stone mounted adjacent the other end of 10 the respective adjustable arms and adapted to impinge upon the internal periphery of the element being ground, resilient means adapted to act upon the frame, whereby the gem stones may be held in impinging contact 15 with the surface of said element while being ground, an indicating device and means for actuating the indicating device, whereby a gauge reading may be obtained to determine changes made in the diameter of the bore 20 of the element being ground while being acted upon by a grinding wheel.
2. In a device for determining the internal diameter of an annular element while the same is being ground, means attached to 25 a grinding machine for supporting a frame, a frame vertically adjustable upon said supporting means and including, an oscillating member, a plurality of arms, vertically adjustable upon the oscillating member, elongated members adjustably carried by said arms fitted with gem stones and adapted to 30 bear upon the periphery of the bore of the annular element, a dial indicator, and means for actuating the indicator, whereby a gauge 35 reading may be obtained to determine 40

3. In a device of the character described, a bracket adapted to be secured to the frame of a grinding machine; a standard pivoted 45 to the bracket provided with a depending arm; a bolt projecting from the wall of the bracket extending through an opening in the arm; a spring mounted upon said bolt adapted to bear upon the arm to tilt the 50 standard; means for limiting the tilting action of the standard; a yoke-shaped element vertically adjustable upon said standard; an oscillating frame pivoted in said yoke-shaped element including a vertically disposed member; a plurality of adjustable arms secured to said vertically disposed member; bars adjustable laterally of and secured to said adjustable arms, the said bars having a gem stone fitted to one end of each 55 bar and adapted to impinge upon the inner wall of an annular element to be ground; a dial indicator and means actuated by one of the adjustable arms, whereby a gauge 60 reading may be obtained of the internal element while it is being ground.

4. In a device of the character described, a standard, a frame means connecting said frame and said standard, said frame including a vertical rod, and being capable of 70 oscillation on said connecting means toward and away from the work, a plurality of independently adjustable arms on said rod, and means on the adjustable arms for engaging the interior of the work while being 75 ground.

In testimony whereof, I sign this specification.

FREDERICK JACKSON PRATT.
